UNITED STATES PATENT OFFICE.

WALLACE W. PARMETTER, OF ELDRED, PENNSYLVANIA.

DRILL-ROPE COUPLING.

No. 890,091.

Specification of Letters Patent.

Patented June 9, 1908.

Application filed April 15, 1907. Serial No. 368,282.

To all whom it may concern:

Be it known that I, WALLACE W. PARMETTER, a citizen of the United States, residing at Eldred, in the county of McKean and State of Pennsylvania, have invented new and useful Improvements in Drill - Rope Couplers, of which the following is a specification.

This invention relates to coupling devices designed especially for connecting wires or other cables to drill tools and has for its object to provide a comparatively simple, inexpensive device of this character, which in practice will effectually couple the cable to the tool, one which permits of the parts being conveniently disconnected when circumstances require and one whereby the cable will be firmly and securely attached to the tool.

With these and other objects in view, the invention comprises the novel features of construction and combination of parts more fully hereinafter described.

In the accompanying drawings, Figure 1 is a view partly in section of a coupling device embodying the invention. Fig. 2 is a section taken centrally and longitudinally through the device. Fig. 3 is a cross section taken on the line 3—3 of Fig. 2 and showing the parts on an enlarged scale. Fig. 4 is a similar view taken on the line 4—4 of Fig. 2. Fig. 5 is a detail perspective view of one section of the core. Fig. 6 is a perspective view of one of the clamping members viewed from its inner face. Fig. 7 is a similar view of the clamping member a viewed from its outer face.

Referring to the drawings, 1 designates a tubular body portion or casing having a longitudinally extended internal chamber or bore 2 of conically tapered form from its lower toward its upper end and terminating at the latter in a straight portion 3, there being extended through the casing from the chamber 2 a central longitudinal opening 4 adapted to accommodate a cable 5.

Disposed within the chamber 2, which is internally threaded at its lower end as at 6 for coupling engagement with a drill tool, is a tubular core 7 conically tapered to conform to the chamber 2 and comprising a pair of component parts or sections 8 having at their upper ends reduced threaded extensions 9 and at their lower ends transverse grooves 55 forming seats 10, there being projected downwardly from the lower ends of the sec-

tions 8 engaging pins or stems 11 adapted to project through openings 12 provided in a clamping member or disk 13 adapted to seat beneath the slotted lower end of the core and to be held in place by means of nuts 14 tapped onto the lower ends of the pins 11.

The sections of the core 7, which is provided on its interior with a pair of opposed splines or feathers 15, are connected in assembled order by means of a coupling nut 16 threaded onto the extensions 9 which it will be understood are of semi-circular form in cross section and conjointly form a reduced tubular neck having a longitudinal passage 70 or bore 17 disposed in alignment with the bore 4 to accommodate the cable 5 and leading upwardly from the chamber 18 formed in the core 7, it being observed that the nut 16 is in practice received within the straight 75 portion 3 of the chamber 2.

Arranged within the core chamber 18 is a pair of coöperating clamping members 19 of diminishingly tapered form from their lower toward their upper ends and provided on 80 their outer faces with opposed longitudinal grooves or channels 20 designed to receive the splines 15 to fix the clamping members against rotation relative to the core 7, the clamping members which are of semi-circular form in cross section to conjointly embrace the cable 5, being provided on their inner faces with spiral grooves 21 pitched to conform to and receive the twisted strands 85 of the cable.

The cable 5 is untwisted at its lower end throughout a suitable portion of its length to provide separate strands 22 adapted to seat severally in the grooves 10, while applied around the cable at the upper ends of 95 the loose strands is a tie member or band 23 which serves to confine and prevent further untwisting of the cable strands.

In practice, to assemble the parts of the coupling the cable is first passed longitudinally through the outer casing 1 and the sections of the core 7 containing the clamping members 19 applied and secured by the coupling nut 16 which, as will be understood, is passed onto the cable before applying the 100 sections of the core to the latter. The loose strands 22 are then seated in the grooves 10 and secured by the clamping disk 13 which is seated upon the pins 11 and fixed in place by the nuts 14. After the parts of the coupling have been assembled the core is drawn 105 upward into the casing 1 and the latter 110

screwed onto the end of the drill 2. It will be particularly observed that owing to strands 22 being clamped in the slots 10 by means of the disk 13 and the cable engaging 5 at a point above its lower end by means of the clamping members 19 which will under the action of upward strain on the cable be caused to clamp the latter, the cable is securely held against disengagement from the 10 coupling and consequently from the tool, while at the same time the parts may be readily disconnected when circumstances require.

What I claim is:

- 15 1. A coupling device of the type described comprising a casing having an internal chamber of reduced diameter at its inner end, said casing being formed for engagement with a tool and having an opening or bore to accommodate an operating rope, a core arranged in said chamber and having a longitudinal bore through which the rope extends, a pair of coöperating clamping members arranged within the core and having spiral 20 grooves to conform to the spiral twist of the rope, and a clamping plate secured to the end of the core and adapted to coöperate with the latter to clamp the loose strands of the coöperating ropes extending around the outer end 25 of the core.
- 30 2. A coupling device of the class described comprising a casing having an internal chamber conically tapered from its outer toward its inner end, said casing being formed for engagement with a drill tool and provided with a rope receiving bore leading from said chamber, a hollow core arranged within and conically tapered to conform to said chamber, said core being provided with a longi-

tudinal opening to receive the rope and at its 40 outer end with transverse grooves forming seats, a pair of coöperating clamping members arranged within the core and having spiral grooves to receive and fit the twisted strands of the rope, the clamping members 45 and inner walls of the core being correspondingly tapered to cause a clamping action of the members and a clamping plate attached to the end of the core for securing within the grooves the loose terminal strands of the 50 coöperating rope.

3. A coupling device of the class described comprising a casing having an internal chamber, a hollow core fitted against movement in one direction within the chamber, said core 55 consisting of a pair of component sections, means for detachably connecting said sections together, a rope extended into the casing and through the core and provided at the outer end of the latter with a plurality of 60 loose strands, coöperating clamping members arranged in the core and internally grooved to fit the twisted strands of the rope, the clamping members and inner walls of the core being tapered to cause a clamping action 65 of the members under movement in one direction, the loose strands of the rope being adapted to extend around the adjacent end of the core, and a clamping plate removably attached to the latter for clamping engagement with said strands.

In testimony whereof, I affix my signature in presence of two witnesses.

WALLACE W. PARMETER.
